UNITED STATES PATENT OFFICE.

WILLIAM WHITE, OF NEW YORK, N. Y., ASSIGNOR TO CLARENCE WHITMAN & CO., OF SAME PLACE.

DESIGN FOR A BEDSPREAD.

SPECIFICATION forming part of Design No. 23,492, dated July 24, 1894.

Application filed June 26, 1894. Serial No. 515,794. Term of patent 3½ years.

To all whom it may concern:

Be it known that I, WILLIAM WHITE, a citizen of the United States, and a resident of the city, county, and State of New York, have invented and produced a new and original Design for Bedspreads, of which the following is a specification, reference being had to the accompanying drawing, which represents a face view of a portion of a bedspread embodying my design, part only being shown in detail, the remainder being shown in outline.

The essential feature of my design is a bedspread the field of which is ornamented with a series of rectangular figures filled in with check and checker-board configurations or effects with adjacent prismatic figures and with a border of zig-zag bands and adjacent checker-board effects or configurations.

In the drawing *a a* are series of rectangular figures filled in with check and checker-board effects or configurations. Adjacent to the rectangular figures are prismatic effects or configurations *b b*. Forming also part of the field of the spread are zig-zag bands *d d*, and adjacent thereto are check and checker-board effects *e f* respectively. The border is composed of zig-zag bands *c c* and adjacent checker-board effects or configurations *g g*.

What I claim is—

The design for a bed-spread substantially as shown and described.

WILLIAM WHITE.
